UNITED STATES PATENT OFFICE

2,051,801

REFRIGERATING APPARATUS

Lawrence A. Philipp, Detroit, Mich., assignor to
 Kelvinator Corporation, Detroit, Mich., a corporation of Michigan

Application June 1, 1934, Serial No. 728,514

12 Claims. (Cl. 62—115)

My invention pertains to a refrigerating system and more particularly to a system in which the refrigerant is first liquefied on the high pressure side and then conducted to the evaporator.

Commercial refrigerating systems have previously employed some device between the high side and low side of the system in an attempt to maintain a predetermined relation between the high pressure liquid and the low pressure liquid or gaseous refrigerant. For this purpose it has been common to use the well known expansion or float valves. However, valves of this nature are very susceptible to many difficulties because of the extremely small apertures and orifices provided for metering the refrigerant. Such very small openings are susceptible to stoppage because of small pieces of dirt, and in time they are also liable to wear because of the wearing action of the fine grit and dirt in the system. In addition to being subjected to stoppage by dirt and wear by grit, such systems were all subject to stoppage because of the freezing of water moisture, were also subject to frosting back, and were relatively expensive to build and service.

It is accordingly an object of my invention to provide a refrigerating system of improved efficiency, simplified construction, and minimized service requirements.

It is a further object of my invention to provide a refrigerating system which avoids the use of all extremely small holes and orifices for metering the refrigerant and the attendant difficulties of line frosting and frequent servicing.

It is also an object of my invention to provide liquid refrigerant responsive means in a refrigerating system for controlling the flow of condensed refrigerant to the evaporator in conjunction with liquid refrigerant responsive means for intermittently releasing predetermined quantities of the condensed refrigerant.

Another object of my invention is to provide means in conjunction with an intermittently operated refrigerant compressor unit for intermittently releasing quantities of the condensed refrigerant to the evaporator.

In accordance with my invention two liquid level responsive means are connected in series relation between the refrigerant condenser and the refrigerant evaporator. The first liquid level responsive means connected to the condenser comprises a liquid receiving vessel having a syphon one end of which is opened to the interior of said vessel. The other end of the syphon opens into a float chamber. In operation liquid fills the syphon vessel to a predetermined level where

it primes the syphon. A predetermined quantity of liquid then flows from the vessel into the float chamber. As soon as the liquid refrigerant in the float chamber attains a predetermined level, the float is lifted and operates a valve through a leverage mechanism. The opening of the valve releases the refrigerant from the float chamber to the evaporator. In this arrangement, the refrigerant regulating valve is either open or shut and the use of expansion valves and restricted orifices in the system is avoided.

The invention itself, however, both as to its organization and its method of operation, together with additional objects and advantages thereof, will best be understood from the following description of specific embodiments, when read in conjunction with the accompanying drawings in which:

Fig. 1 is a diagrammatic view representing a refrigerating system controlled in accordance with my invention; and

Figs. 2 and 3 are views showing modifications in which the syphon vessel and the float chamber are united in a unitary structure.

Referring more specifically to the drawings, the apparatus shown in Fig. 1 comprises a compressor 1 for compressing the vaporized refrigerant which it draws through a suction line 2 from the refrigerant evaporator 3. The compressor 1 is driven by an electric motor 6 which is controlled by a snap action switch 7 through which it may be connected to the line conductors. The switch 7 is actuated by an expansible bellows 8 interconnected through a pipe 9 to a thermo bulb 10 which is mounted adjacent the evaporator 3 or in the space cooled thereby in the usual manner. The switch 7 is quickly operated by a snap action mechanism 13 to energize the motor 6 from the line conductors 16 and 17 when the temperature adjacent the thermo bulb rises to a predetermined maximum.

As the refrigerant vapor is compressed it passes from the compressor 1 through a condenser 21 where its latent heat of vaporization is dissipated into space in the well known manner. From the condenser 21 the liquefied refrigerant passes through a suitable conduit 25 into a liquid receiving vessel 26. The vessel 26 encloses a curved pipe 27 of inverted U formation which comprises a syphon. One leg 28 of the U-shaped syphon 27 is extended and passes through the bottom plate 29 of the vessel 26 to which it may be hermetically sealed and rigidly secured in any suitable manner, as by welding or soldering. The other leg 30 of the syphon 27 is shorter and is sup-

ported in open spaced relation adjacent the bottom 29 of the vessel. The bottom plate 29 of the syphon vessel 26 may be removably secured to the side walls thereof in any suitable manner as by 5 threadable engagement therewith.

A float chamber 31 comprising cup shaped side walls 30, which are inverted upon a removable base plate 32, encloses and supports an automatic float actuated valve. The valve comprises a reciprocatable piston member 33 which may be moved into sealing relation with a valve seat 34 to shut off the flow of liquid from the chamber 26. The valve is actuated by means of a suitable leverage mechanism. As shown, this mechanism 15 may comprise a pair of pivoted arms 35 the free ends of which are connected by a U-shaped bracket 36 to a buoyant float 37.

The syphon vessel 26 is connected through the extended leg 28 of the syphon pipe 27 into the 20 sidewall of the float chamber 31. A vent pipe 41 is connected from the upper portion of the float chamber 31 to the upper end of the syphon vessel 26 in order to vent the float chamber and permit 25 the liquid to enter from the syphon vessel. From the float chamber 31 the liquid refrigerant passes through a conduit 44 to the header 45 of the evaporator 3.

In operation the thermostatically controlled 30 switch 7 starts the compressor unit whenever the temperature within the space adjacent the evaporator rises to a predetermined value. As the compressor operates the compressed refrigerant passes through the condenser 21 where its heat is dissipated and the condensed refrigerant passes 35 down to the syphon vessel 26. When the liquid rises to the predetermined level in the vessel 26 it primes the syphon pipe 27 and liquid starts to flow into the float chamber 31.

After a predetermined amount of liquid has 40 passed into the float chamber the float is lifted to actuate the leverage mechanism which in turn opens the valve 33. After a predetermined quantity of liquid has passed from the syphon vessel the open end of the syphon is no longer immersed. 45 The syphon then goes dry and no more liquid will pass from the syphon vessel 26 until it has again been filled. The evaporator thus intermittently receives predetermined quantities of the condensed refrigerant through valve means which 50 has a positively open and a positively closed position thereby avoiding the use of expansion or throttling valves having very small orifices with the attendant disadvantages. In this manner of operation, intermittent cooling and defrosting of 55 the evaporator can be accomplished. In the operation of my system relatively large quantities of refrigerant are dumped into the evaporator where it flashes off along the VP curve. Under these conditions the refrigerant vapor is very 60 dense and the compressor operates more efficiently.

In order to provide a more convenient and compact assemblage of elements the float valve and the syphon vessel may be combined in a unitary 65 structure as illustrated in Fig. 2. In this embodiment of my invention the sidewalls of the syphon chamber 51 may be extended downwardly to provide a second compartment 52 thereunder, to enclose the valve 33 and its actuating float 37 which 70 is mounted upon an end plate 53 threadably received or otherwise secured in the end of the casting. A vent pipe 54 is provided which rises directly from the syphon base plate 55 to the upper end of the syphon vessel. In this embodiment 75 the pipe 58 at the upper end of the syphon vessel

is connected to the condenser and the pipe 59 from the lower end of the float valve chamber is connected to the evaporator. In this manner the two housings are combined in one and the two interconnecting conduits are eliminated thereby 5 providing a more compact unit which may be more conveniently installed.

A combined unitary structure may also be provided by extending the walls of the float valve chamber sufficiently to receive a liquid receiving 10 syphon vessel 62 which is mounted above the float as shown in Fig. 3. In this embodiment the inverted U shaped syphon pipe 63 may be supported over or through the upper edge of the liquid receiving syphon vessel 62 in such a manner that its longest branch is suspended in the float chamber and the shorter branch is suspended in the liquid receiving vessel 62 where it terminates adjacent the bottom thereof. In this embodiment the upper pipe fitting is connected to the condenser and the lower to the evaporator as in the previous modifications.

It will be seen that I have provided a refrigerating system of improved efficiency, which is of simplified construction requiring a minimum of 25 service attention.

While it is necessary for the purposes of illustration to describe the several disclosed forms of my invention in detail, it will be apparent that the invention is not so limited and that other 30 forms and applications thereof are embraced within the scope of the appended claims.

I claim as my invention:

1. In combination a refrigerant evaporator, refrigerant compressor-condenser means, means 35 for actuating said compressor-condenser intermittently in accordance with temperature conditions, means operatively interconnecting said compressor-condenser and said evaporator including syphon means operable during the operation of the compressor for periodically passing 40 predetermined quantities of liquid refrigerant.

2. In combination a refrigerant condenser, a refrigerant evaporator, means operatively interconnecting said condenser and evaporator including a liquid receiving vessel, and syphon means 45 responsive to the accumulation of liquid refrigerant in said vessel for dumping quantities of liquid into the evaporator.

3. In combination a refrigerant condenser, a refrigerant evaporator, means operatively interconnecting said condenser and evaporator including a syphon vessel and a float valve chamber connected in series relation for intermittently 55 discharging predetermined quantities of liquid to said evaporator.

4. A refrigerating system comprising a refrigerant evaporator, a refrigerant compressor, a refrigerant condenser, means operatively interconnecting said compressor, condenser and evaporator including a refrigerant receiving syphon vessel and a refrigerant receiving float chamber, a syphon in said vessel for controlling the flow of refrigerant to the float chamber, and a 65 float actuated valve in said chamber for intermittently discharging quantities of refrigerant into said evaporator.

5. The combination with a refrigerating system comprising a high side portion, a low side 70 portion, and a float type valve for regulating the flow of refrigerant from the high side portion to the low side portion, of means providing a dumping action of said float valve, said means comprising a refrigerant receiving vessel dis- 75

- posed between said high side portion and said float valve and a siphon therein for intermittently discharging quantities of refrigerant from said vessel to the float valve.
- 5 6. The combination in a refrigerating system comprising a high side portion and a low side portion of means for regulating the flow of refrigerant from the high side portion to the low side portion comprising a vessel for receiving refrigerant from the high side portion, and siphon means for intermittently discharging quantities of refrigerant from said vessel.
- 10 7. The combination in a refrigerating system comprising a high side portion and a low side portion of means for regulating the flow of refrigerant from the high side portion to the low side portion comprising a vessel for receiving refrigerant from the high side portion, siphon means for intermittently discharging quantities of refrigerant from said vessel, a chamber for receiving the refrigerant discharged from the vessel and a float actuated valve in said chamber for intermittently discharging the stored refrigerant to the low side of the system.
- 15 8. The combination in a refrigerating system comprising a high side portion and a low side portion of means for regulating the flow of refrigerant from the high side portion to the low side portion comprising a vessel for receiving refrigerant from the high side portion, siphon means for intermittently discharging quantities of refrigerant from said vessel, a downwardly extended portion of said vessel comprising a chamber for receiving the refrigerant discharged from the vessel, a vent conduit for discharging gas from said chamber into said vessel and a float actuated valve in said chamber for intermittently discharging the stored refrigerant to the low side of the system.
- 20 9. The combination in a refrigerating system comprising a high side portion and a low side portion of means for regulating the flow of refrigerant from the high side portion to the low side portion comprising a vessel for receiving refrigerant from the high side portion, siphon means for intermittently discharging quantities of refrigerant from said vessel, a float actuated valve in said chamber for discharging the stored refrigerant to the low side of the system.
- 25 10. The combination in a refrigerating system comprising a high side portion and a low side portion of means for regulating the flow of refrigerant from the high side portion to the low side portion comprising a vessel for receiving refrigerant from the high side portion, siphon means for intermittently discharging quantities of refrigerant from said vessel, a separately disposed chamber for receiving the refrigerant discharged from said vessel, a vent conduit connected from the upper portion of said chamber to the upper portion of said vessel and a float actuated valve in said chamber for intermittently discharging stored quantities of refrigerant to the low side of the system.
- 30 11. Refrigerant flow controlling means for regulating the flow of refrigerant from the high side to the low side of a refrigerating system comprising a float chamber, a float actuated valve in the lower portion of said chamber, a bucket mounted in said chamber above said valve, inlet means for discharging refrigerant into said bucket, and a siphon mounted in a side wall of said bucket for intermittently discharging refrigerant therefrom.
- 35 12. Refrigerant flow controlling means for regulating the flow of refrigerant from the high side to the low side of a refrigerating system comprising a unitary housing, a siphon base plate in said housing for separating the enclosure into a siphon vessel and a float valve chamber, inlet means for admitting refrigerant to the vessel, a siphon extending above and through said base plate for intermittently discharging refrigerant therethrough, a vent conduit extending through said base plate and a float actuated valve in said float chamber discharging quantities of refrigerant therefrom.
